UNITED STATES PATENT OFFICE.

JEFFERSON H. MILLSAPS, OF WASHINGTON, DISTRICT OF COLUMBIA.

ELEVATOR.

SPECIFICATION forming part of Letters Patent No. 782,159, dated February 7, 1905.

Application filed April 22, 1904. Serial No. 204,387.

To all whom it may concern:

Be it known that I, JEFFERSON H. MILLSAPS, a citizen of the United States, residing at Washington, District of Columbia, have invented certain new and useful Improvements in Elevators; and I do hereby declare the following to be a full, clear, and exact description of the invention, such as will enable others skilled in the art to which it appertains to make and use the same.

This invention relates to elevators, and more particularly to safety appliances therefor for preventing descent of the car should the lifting-cable break.

The object of the invention is to provide a construction wherein there will be provided a positive obstruction to the downward movement of the car so connected and arranged that as the car moves upwardly it will be gradually shifted into position beneath the car or into active position, and as the car moves downwardly or is lowered by its lifting-cable the obstruction will be gradually removed, the means for shifting the obstruction being connected with the car through the medium of the lifting-cable, so that when the lifting-cable breaks the shifting mechanism will be no longer operative and the obstruction will remain in the path of downward movement of the car, so that the latter will engage it and be supported thereby.

In the drawings forming a portion of this specification, and in which like numerals of reference indicate similar parts in the several views, Figure 1 is a vertical section through an elevator-shaft having guide-rails, a car, and connected mechanism embodying the present invention. Fig. 2 is a perspective view showing a portion of a guide-rail and one of the uprights of the frame in which it is slidably mounted. Fig. 3 is a section on line 3-3 of Fig. 1.

Referring now to the drawings, there is shown a portion of an elevator-shaft comprising uprights 5 and 6, there being a pair of uprights 5 and 6 at each side of the shaft, and between each pair of uprights is arranged a guide-rail 7. In the inner or mutually adjacent faces of each pair of uprights 5 and 6 there are formed grooves 9, which are in-

clined in the direction of the adjacent wall of the shaft—that is, the ends of the grooves next to the wall of the shaft are higher than the ends next to the car. Each of the guide-rails is provided with pins 10, that project laterally from the guide-rail and slidably engage the corresponding grooves 9, so that when the guide-rail is lifted these pins will pass outwardly and upwardly in the grooves, so that the guide-rails 7 and 8 will be moved apart. Between the guide-rails is arranged a car 11, and it will be noted that the sides of the car which are in contact with the guide-rails converge downwardly, so that the car is of wedge shape, and it will be further noted that the guide-rails 7 and 8 are converged downwardly to correspond to the sides of the car. The spacing of the guide-rails in the plane of the bottom of the car is equal to the width of the car, while the spacing of the lower ends of the guide-rails is less than the width of the car, the guide-rails being of such weight that the lateral pressure due to the wedging action of the car between the guide-rails is not sufficient to move the guide-rails laterally and upwardly from engagement with the car, and hence unless positively raised the guide-rails serve to positively prevent downward movement of the car. To shift the guide-rails to correspond to the movement of the car, the lifting-cable 15, which is attached to the car, is passed around a drum 16 and then over direction-pulley 17, and then downwardly to the winding-drum 18, which is operated in the usual manner to raise and lower the car. By passing the cable around the drum 16 several times sufficient friction is acquired to insure positive rotation of the drum from the cable.

On the end of the drum 16 is a pinion 19, which engages a gear-wheel 20, having a pinion 21, engaging a gear-wheel 22 on a winding-drum 23, it being understood that this reducing-train may be varied as desired to secure the proper speed of rotation of the drum 23. A cable 24 is attached to the drum 23 and to the guide-rail 7, while a second cable 25 is attached to said drum and after passing over a direction-pulley 26 is attached to the guide-rail 8, so that as the car 11 rises and moves

downwardly the cables 24 and 25 are unwound or wound up to lower and raise the guide-rails. Should the cable 15 break at any point between the winding-drum 18 and the car 11, 5 the car will drop or start to drop; but the tension of the cable 15 being removed the frictional engagement thereof with the drum 16 will cease and the drum 23 will be permitted to rotate to unwind the cables 24 and 25 therefrom sufficient to insure immediate lodgment of the car between the guide-rails. Inasmuch 10 as the guide-rails are in comparatively close relation to the car as the latter moves upwardly, the actual drop of the car will be practically nothing.

It will be understood that in practice modifications of the specific construction shown may be made and any suitable materials and proportions may be used for the various parts 20 without departing from the spirit of the invention.

It will be noted that with the present construction the guide-rails serve as counterbalances for the car.

25 What is claimed is—

1. The combination with an elevator-car, of downwardly-convergent guide-rails between which the car is adapted to wedge, a lifting-cable connected to the car and means operable 30 by the cable only when the latter is intact, for shifting the guide-rails toward and away from each other.

2. The combination with an elevator-car, of downwardly-convergent guide-rails between 35 which the car is adapted to wedge, a lifting-cable connected to the car and means operable by the cable only when the latter is intact, for shifting the guide-rails away from each other.

3. The combination with an elevator-car, of

guide-rails, a lifting-cable connected to the 40 car and means operable by the cable only when the latter is intact for shifting the guide-rails laterally into and out of position for wedging of the car therebetween.

4. The combination with an elevator-car 45 and a winding-drum, of a cable connected with the car and drum for lifting the car, means for holding the car against downward movement and with which the car is in constant engagement, and means operatively connected with the lifting-cable and operable thereby when the cable is intact, for shifting said supporting means to correspond to the position of the car.

5. The combination with an elevator-car 55 and its lifting-cable, of a shiftable obstruction in the path of downward movement of the car and means operable by the cable only when the latter is intact, for shifting said obstruction progressively out of that portion of the 60 path of the car that is occupied by the car.

6. An elevator comprising a movable guide-rail and means for connecting the same to the operating mechanism so that as the car moves upwardly or downwardly, the guide-rail is 65 shifted outwardly and inwardly, the guide-rail being at all times in contact with the car, substantially as described.

7. An elevator comprising upright supports and guide-rails having a pin-and-groove 70 connection with said supports, substantially as described.

In testimony whereof I affix my signature in presence of two witnesses.

JEFFERSON H. MILLSAPS.
